DESIGN FOR A HANDBAG

Max C. Demerer, Chicago, Ill.

Application October 6, 1945, Serial No. 122,614

Term of patent 7 years

(Cl. D87—3)

To all whom it may concern:

Be it known that I, Max C. Demerer, a citizen of the United States, residing in Chicago, in the county of Cook and State of Illinois, have invented a new, original, and ornamental Design for a Handbag, of which the following is a specification, reference being had to the accompanying drawing, forming part thereof.

Fig. 1 is a front perspective view of a handbag showing my design in closed position.

Fig. 2 is a perspective view of the handbag with the outer pockets in partly open position.

Fig. 3 is a top plan view of the handbag shown in Figs. 1 and 2 in closed position, and

Fig. 4 is a top plan view thereof, with the central part of the bag in open position.

I claim:

The ornamental design for a handbag, substantially as shown.

MAX C. DEMERER.
